POWER GENERATING AND DRIVING MEANS

Edwin T. Wyman, Brookline, Mass.

Application November 13, 1936, Serial No. 110,694

4 Claims. (Cl. 60—14)

This invention relates to power generating and driving means, and more specifically to a novel and improved combined internal combustion and compressed gas or air engine.

5 In the drawings of the illustrative form of my novel engine described herein,

Fig. 1 is a side elevation, partly in section;

Fig. 2, a similar view of a modified form of construction, including the internal combustion 10 engine in combination with a conventional compound steam or vapor engine;

Fig. 3, a detail elevation on an enlarged scale, partly in section, of one of the gas admission valves to the gas compression, mixing and steam generating reservoir; and

15 Fig. 4 is a section, on an enlarged scale, of the valves 35, 36, in the water supply by-pass system.

Fig. 5 is a vertical, diagrammatical section, in 20 part, of the pressure controlling valve for the reservoir.

Referring first to Fig. 1, my novel power generator construction comprises an internal combustion engine 1, of any preferred type, as gasoline 25 or Diesel, of substantially conventional construction, of two or four cycle type, with a gas, hot air and steam generating, mixing and compression reservoir 2, operatively connected thereto, and properly protected by asbestos or other 30 suitable insulation, 450.

While, for reasons well known to those skilled in the art, the internal combustion engine of conventional type possesses a great many practical advantages over other types of engines, both for 35 stationary use and as a motor for moving vehicles, it is well known that it is very wasteful in loss of energy through the exhausted burnt gases and the heat loss through cooling of the cylinder, many authorities estimating the loss 40 at a substantial percentage of horsepower per pound of fuel gas consumed, depending upon the type and size of the engine.

It is one object of my invention to prevent this great waste of power by recovering a part of it, 45 and utilizing it separately or jointly with that normally generated by the engine.

To that end, I provide the reservoir 2, as stated.

While it is not necessary that the mixing chamber be mounted upon the engine as shown, I 50 prefer that construction, as it has some advantages of convenience and compactness.

In the present case, I mount the mixing chamber 55 2 directly upon the engine head 3, or over it and independently supported, so that close operative connection with the engine head may be had.

and in the head are mounted a plurality of inlet valves 4 to admit directly to the reservoir from the head a portion of the burnt gases and products of combustion before they have become a part of the exhaust. To effect this novel result, I prefer 5 to provide one such inlet valve for each cylinder of the engine, and locate it directly over a cylinder 5.

This valve may be of any suitable construction, and herein, Fig. 3, comprises a cylindrical housing 6, with a flange 7, by means of which it is properly secured to the bottom of the reservoir 2 and the engine head 3, and depending in a valve pocket 17, surrounded if necessary by a water jacket 8, which registers with an opening, 8a, 10 into the usual jacket, not shown, in the head or block for water cooling purposes. Within the housing, and supported thereby, are struts 9, which carry a yoke-like valve cage 10, in the lower end of which is mounted the stem 11 of an 15 inlet valve 4, seated in the engine head 3. The passage 13 between the cage 10 and head 3 conducts the burnt gases from the cylinder 5 to the reservoir. The valve stem is provided with a suitable spring 14, seated at its lower end against 20 a nut 155, movable upon the valve stem, and at the opposite end, seated against a web 15 to adjustably hold the valve 4 normally seated to close 25 the inlet port 16 in the head 3.

The amount of power developed by the internal 30 combustion engine and that developed by the second source of power or supplementary engine, also the heat transmitted to the cooling water and that lost by the exhaust, depends upon the pressure carried in the mixing chamber in excess 35 of the necessary compression pressure in the cylinder for ignition.

The higher the controlled pressure is carried in the mixing chamber after it is once charged, the more power the internal 40 combustion engine will develop and transmit through its crank-shaft, and the less energy will be transferred to the mixing chamber available 45 for the second source of power or the supplementary engine and the greater the heat loss in the operation of the power plant. The ideal pressure carried in the mixing chamber would be 50 the amount necessary to heat the feed water for use as hereafter described to the proper temperature with the minimum loss of heat through the cooling system and exhaust.

This valve spring 14 is of such strength, and is so adjusted by means of the nut 155, that it, plus the compression in the mixing chamber, will resist the compression force in the cylinder, and the explosion force up to a certain point, and the 55

valve 4 then opens to permit the heat and energy above that point to pass into the mixing chamber, the force of the exhaust and gases below that point escaping by the conventional exhaust ports, not shown, in the engine block 1.

This novel construction permits the prompt and effective saving of a substantial part of the compression force created by the explosion and the creating of useful compression in the reservoir, 10 with a minimum loss of heat and power, before the forces have been dissipated by travel through the usual exhaust exits and pipe in the conventional manner.

When it is realized that, at the instant of explosion, the temperature in the cylinder of an 15 internal combustion engine is frequently about 2500° F., or even higher, and that the exhaust following the explosion has a temperature of about 1300° F., on an average, with an exhaust 20 pressure of from 25 to 35 pounds per square inch, or even more, it will be evident that a tremendous amount of power, say from 15 to 20 pounds per square inch, and a considerable amount of heat, are wasted at the end of every stroke.

As by my novel construction a substantial portion 25 of the heat and exploded gases are trapped in the mixing chamber, the heat loss through cooling water and exhaust is far less than in the case of the usual internal combustion engine.

The reservoir, Figs. 1, 2, may be provided with 30 a steam generating fin 17, of convenient width and length for a purpose to be described. To permit the starting of the engine in the usual manner, as by a motor, compressed air or crank, 35 I provide a novel valve-locking camshaft 18, extended longitudinally of the mixing chamber 2, and mounted in its end walls or other supports, and directly over the valve stems 11. The shaft is provided with cams 20, each positioned so that, by rotation of the shaft 18, as by the handle 21 40 or any suitable arrangement, before starting the engine, the cams may lock the stems 11 against vertical movement, and so close the ports 16 against the escape of the exploded gases, which would reduce the explosive force against the piston 45 tons, and by this arrangement I retain all the advantage of normal internal combustion engine functions for engine starting. Afterward, the valve stems may gradually be released, and the valves permitted to function in the normal manner.

To use the heat and compression developed in the mixing chamber, and incidentally to cool the burnt gases within the mixing chamber to the desired working temperature, Figs. 1, 2, I provide 55 a water supply comprising a pipe 23 from any source of supply, not shown, preferably from the water jacket of the internal combustion engine, and leading to a pump 24, operated through a 60 bell-crank lever 244 and link 245 from the cam 246 on the shaft 50 and thence to a compression tank 25, and through a heater 26 of suitable construction, in the exhaust manifold 21, and then to the valve housing 28. The pipe 233 leads from 65 the tank 23 to the nozzle 234 of conventional construction, by means of which water may be forced into the mixing and compression chamber, where the water is vaporized and steam formed, as the result of the heat from the exhaust gases therein. 70 The supply of water is controlled by any convenient thermostatic device, as a rod 29 of suitable material, as copper, sufficiently sensitive to variations in temperature to expand and con-

tract, and enclosed in a channel 30 in the wall of the mixing chamber.

The supply pipe 23 is provided with check valves 32, 33, permitting flow of water to the pressure tank 25 and mixing chamber 2, with a pressure-regulator 35, as a diaphragm valve, see Fig. 4, normally closed by the spring 355 in the barrel 356, and seated against the adjustable plug 357 therein, which spring yields under predetermined pressure to permit the diaphragm to withdraw 10 the valve head 36 and the water from the pump to be returned through the pipe 34 to the pipe 23.

While the water fed into the reservoir by the pump 24 will lower the temperature in the reservoir, the water will, as stated, at the same time, 15 when fed in proper quantity, be heated to the steam forming degree. A part of the energy in the hot combustion products is transferred to the water to form steam, by the feeding of water into the mixing chamber containing the products of combustion. This mixture of steam and combustion products at a controlled temperature is utilized to drive a second source of power or supplementary engine, as will be presently described. The fin 17 previously referred to, and 25 the shorter upright fins 37 on the reservoir wall, all become very hot, and when water is injected into the boiler, the fins by their additional heat-radiating surfaces assist in generating steam, on the principle of the flash boiler and assist in 30 thoroughly mixing the steam and hot gases.

To prevent any water spray, or water, through any accident, from entering the valve housing 6, I provide the baffles 38 on the reservoir bottom, and overhanging the valve ports.

Automatic control of the pressure in the reservoir is obtained, Fig. 5, by means of a pressure control valve 39 of suitable type as having a diaphragm 391 resting against one end of a spring 392 in the barrel 393 and seated at its opposite end against the adjustable plug 394, and responsive to varying degrees of pressure, and which, through any convenient connection to control the functioning of the engine, as the lever 40, link 41 to operate the fuel supply valve and carburetor 42 in the feed pipe 43, increases, reduces, or even stops, the supply of fuel to the engine.

To further obtain the benefit of the unexpended force and heat of the compressed and hot products of combustion and the steam generated in the reservoir, Figs. 1, 2, I provide a vapor and air impact engine or turbine 45 to be driven thereby, in a suitable housing 46, connected by pipe 47 with throttle valve 48 to the reservoir. This turbine may be of any conventional form, as the De Laval, and connected by gears 49, with the shaft 50 of the engine.

By this means, considerable extra power is made available through the turbine at high speed, either for separate use or by it jointly in connection with the engine by shaft 50.

The reservoir is provided with a suitable pressure gauge 51 and a temperature gauge 52. The temperature is not allowed to reach a point that will be injurious to the turbine, as the temperature in the reservoir is automatically controlled by the thermostat 29, and the pressure in the reservoir is automatically controlled by the pressure regulator 39, and the pressure in the turbine by the 65 throttle 48.

In Fig. 2, the engine 1 is shown in combination with a reciprocating hot air engine 53 of the compound type, being directly connected thereto, the latter engine having the high pressure cylinders 70 75

54 with pistons 544, and the low pressure cylinder 55 with pistons 555 connected to, the same shaft 50 with the internal combustion engine, the high pressure cylinders being supplied by steam and hot products of combustion by the pipe 56 from the reservoir 2, and controlled by the throttle valve 57.

The foregoing novel power plant is much more economical than the ordinary internal combustion engine, and provides an increased amount of power, and with energy that ordinarily is lost. The complete machine has both the quick starting advantages of an internal combustion engine and the reserve and flexibility of a steam engine.

My invention is not limited to the precise construction shown herein, but may be modified in many details, without departing from the spirit of the claims, and within the scope thereof.

I claim:

1. An internal combustion engine having, in combination, means for mixing the products of combustion with another fluid, said means comprising a mixing chamber operatively connected to the engine cylinders to receive said products; yieldingly-closed valves automatically controlling said connections to admit desired quantity of the products to the chamber; additional fluid supply means for the chamber including a supply pipe and heater therefor; and means for closing the cylinder connections to said mixing chamber to cut out the chamber to conserve the explosive power of compression in the cylinders for starting the engine; and a second engine connected with and driven by the fluid from the internal combustion engine, and means for supplying mixed products of combustion and another fluid to the second engine from the mixing chamber, whereby the internal combustion engine may act to the degree desired as a producer of operating fluids for the second engine.

2. The combination with an internal combustion engine of a mixing chamber to receive the products of combustion from the engine, and a fluid to mix therewith, and a supplementary engine operatively connected with the internal combustion engine and mixing chamber, and operated with fluid from said mixing chamber,

and means for determining electively the quantity and time of admission of the combustion products to the mixing chamber, even to complete exclusion of them temporarily, if desired, said means including normally yieldingly-closed valves and means including a cam rod carrying cams positioned operatively relatively to said valves for closing them entirely at will, said combustion engine operable alone or in combination with the supplementary engine.

3. An internal combustion engine having, in combination, a mixing chamber for its products of combustion, and a water supply therefor; a supplementary engine operable from said mixing chamber and operatively connected with the combustion engine and said chamber; adjustable valves between the cylinders of the combustion engine and the chamber and from the latter to the supplementary engine; a fluid supply means for said chamber, and control means for closing the valves from the combustion engine to the mixing chamber to conserve the power of the engine when starting, said combustion engine operable alone or in combination with the supplementary engine.

4. An internal combustion engine having, in combination, a mixing chamber for its products of combustion, and a water supply therefor; a supplementary engine operable from said mixing chamber and operatively connected with the combustion engine and said chamber; adjustable valves between the cylinders of the combustion engine and the chamber and from the latter to the supplementary engine; a water supply means for said chamber, and control means for closing the valves from the combustion engine to the mixing chamber to conserve the power of the engine when starting; and automatic means for controlling the combustion engine by the pressure in the mixing chamber, and similar means for controlling the admission of additional fluid to the mixing chamber; and shields in the mixing chamber for the engine valves to protect the latter from water supplied to the combustion chamber, said combustion engine operable alone or in combination with the supplementary engine.

EDWIN T. WYMAN.
